UNITED STATES PATENT OFFICE.

GROVER G. TUTTLE, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DRILL-STEEL RETAINER.

Application filed June 2, 1921. Serial No. 474,480.

To all whom it may concern:

Be it known that I, GROVER G. TUTTLE, a citizen of the United States, a resident of Phillipsburg, county of Warren, and State 5 of New Jersey, have invented a certain Drill-Steel Retainer, of which the following is a specification, accompanied by drawings.

This invention relates to drill steel retainers for rock drills, but more particularly to 10 that type of retainer in which the yoke embraces the drill steel and is suitably held or clamped in position upon the front head of the machine.

Such yoke retainers are subjected to 15 severe impact as the collar on the drill steel strikes the yoke and various devices have been employed to cushion or yieldingly hold the yoke to avoid breakage of the parts, some of these devices include bolts and springs, 20 but the breakage is difficult to overcome, and the more complex the parts, the greater the danger of breakage becomes.

The primary objects of the present invention are to simplify the retainer construction, 25 and reduce the chances of breakage by avoiding the use of retainer bolts and supporting the yoke retainer from the front head of the machine by means of main and supplementary springs which cushion the 30 yoke in both directions.

Another object of the invention is to supplement the expansive force of the main springs in holding the retainer, by means of fluid under pressure, which may be the live 35 pressure taken from the supply inlet of the machine. In such case, if the pressure fails for any reason, the main retainer springs still fulfill the function of exerting pressure to cushion the yoke.

Another object of the invention is to make 40 the casings for the springs separate from the front head and mount them to swing relatively to the front head, carrying the yoke retainer with them. This avoids the 45 necessity of pivoting the yoke retainer to the spring casings and permits a simple connection between the retainer and the spring casings.

To these ends the invention is shown in 50 its preferred forms in the accompanying drawings, in which

Figure 1 is a diagrammatic front elevation of the front head of a rock drill having my drill steel retainer applied thereto, parts

of the front head and retainer being shown 55 in vertical section.

Figure 2 is a side elevation of the device, and

Figure 3 is a horizontal section plan view 60 of Figure 1 on the line 3—3.

Referring to the drawings, A represents diagrammatically the front head of a rock drill having the nose piece B, adapted to receive the usual front head bushing C through which the drill steel D having the 65 collar E, is adapted to extend in position to receive the impact blows of the hammer. The front head is provided with the usual lugs F through which the side bolts G extend for clamping the cylinder and front 70 head together. In this instance the front end portion H of the cylinder casing is shown diagrammatically and partly broken away to indicate the relation of the parts.

In accordance with my invention the front 75 head is provided with cushion holding guides J pivoted at opposite sides of the machine and main cushioning means in the form of coiled springs K are guided and held within said guides J. In order to suitably pivot the guides J so that they may swing at each side of the front head, the said front head is conveniently provided with trunnions L and the guides J are mounted on blocks O having socket portions P for the 85 trunnions L. The guides J are adapted to slide longitudinally on said blocks O so that they have a combined swinging and longitudinal movement relative to the front head of the machine. In order to permit 90 longitudinal movement of the guides, the sides are cut away or slotted at Q over the blocks O and trunnions L.

A yoke retainer R is provided with arms or shanks S having stops or collars T, and 95 these yoke arms extend longitudinally through the pivotal blocks O and through the ends U of the guides J. Nuts V on the ends of the yoke arms hold the parts in position. Leather washers or other packing device W over the yoke arms S aid in sealing the chambers X formed within the guides, and sleeves Y within the guides close the openings in the walls of the guides formed by the slots or cut away portions Q. 100

The main springs K are adapted to be compressed between the blocks O and the end portions U of the guides. Supplemental

springs Z in the form of coiled springs over the shanks of the yoke retainer are suitably held between the blocks O and the caps a which bear on the collars T on the yoke 5 arms.

In the operation of the device the main springs K resist the outward thrust of the yoke retainer and the supplemental springs Z resist the thrust in the opposite direction.

10 Passageways b in the main cylinder casing H and front head A communicate through the ports c with the sealed interior of the guides supplying fluid pressure, preferably live air, for assisting the expansive force 15 of the main spring K. In accordance with my construction and spring guides J have a combined pivotal and longitudinal movement bodily relative to the front head. In order to maintain the yoke in operative 20 longitudinal position, the end faces d of the blocks O are preferably transversely grooved as indicated by the dotted lines e so that the yoke arms S may be sprung into and out of the grooves e.

25 I claim:

1. A drill steel retainer for rock drills, comprising swinging and longitudinal movable cushion holding guides at each side of the front head of the machine cushioning 30 means on said guides, a yoke retainer for the drill steel having arms guided in said guides and cushioned by said cushioning means and means for maintaining fluid pressure within said guides to supplement the expansive 35 force of the cushioning means in one direction.

2. A drill steel retainer for rock drills, comprising swinging and longitudinally

movable spring holding guides pivoted at opposite sides of the front head of the machine, coiled springs within said guides, a yoke retainer for the drill steel having arms guided in said guides and cushioned by said springs, and means for maintaining fluid pressure within said guides to supplement 45 the expansive force of the cushioning means in one direction.

3. A drill steel retainer for rock drills comprising swinging and longitudinally movable spring holding guides pivoted at 50 opposite sides of the front head of the machine, coiled springs within said guides, a yoke retainer for the drill steel having arms slidable longitudinally in said guides and cushioned in both directions by said springs, 55 and means for maintaining fluid pressure within said guides to supplement the expansive force of the cushioning means in one direction.

4. A drill steel retainer for rock drills, 60 comprising swinging and longitudinally movable spring holding guides pivoted at opposite sides of the front head of the machine, main and supplementary springs coiled within said guides, a yoke retainer 65 for the drill steel having arms slid able in said guides and cushioned in both directions by said main and supplementary springs respectively, and means for maintaining fluid pressure within said guides to supplement 70 the expansive force of the cushioning means in one direction.

In testimony whereof I have signed this specification.

GROVER G. TUTTLE.
